Valbert & Parker,
Attorneys.

UNITED STATES PATENT OFFICE.

JAMES H. POWERS, OF EVANSVILLE, INDIANA.

LAMP.

No. 1,272,315.

Specification of Letters Patent.

Patented July 9, 1918.

Application filed April 27, 1917. Serial No. 164,924.

To all whom it may concern:

Be it known that I, JAMES H. POWERS, a citizen of the United States, residing at Evansville, in the county of Vanderburgh and State of Indiana, have invented certain useful Improvements in Lamps, of which the following is a specification, reference being had therein to the accompanying drawing.

10 The present invention has reference generally to improvements in acetylene lamps and more particularly relates to acetylene lamps of the type particularly adapted for use on miners' caps.

15 As the primary aim and object, the present invention contemplates the provision of a lamp body consisting of two sections constructed to constitute a carbide receiving and gas generating cup and a superimposed water chamber, novel means being adjustably mounted in the water chamber for controlling the flow of water from the chamber to the carbide cup whereby to consequently regulate the amount of gas generated therein.

20 It is an additional and equally important object of this invention to construct the water feeding and controlling means so as to agitate the carbide within the cup thus facilitating the generation of the gas.

25 As a more specific object, the invention embraces the provision of improved means for removably connecting a reflector to the water chamber and at the same time providing a communication between the gas outlet pipe and the burner tip; and to provide novel means for connecting a finger piece to the water feed tube.

30 Among the other aims and objects of the present invention may be recited the provision of a device of the character mentioned with a view to compactness, and in which the number of parts are few, the construction simple, the cost of production low and the efficiency high.

35 Other objects, as well as the nature, characteristic features and scope of my invention will be more readily apparent from the following description taken in connection with the accompanying drawings and pointed out in the claims.

The preferred embodiment of the present

invention is clearly illustrated in the accompanying drawings, in which:—

Figure 1 is a vertical section of my invention.

Fig. 2 is a transverse section taken on line 2—2 of Fig. 1 in the direction in which the arrows point.

Fig. 3 is a top plan of the top of the water chamber, and

Fig. 4 is a perspective detail.

Similar reference characters are employed in all of the above described views, to indicate corresponding parts.

Referring now, more particularly, to the accompanying drawings I provide a lamp body embodying two sections the lower of which serves as a base and is shaped to form a cylindrical carbide receiving and gas generating cup 1. A threaded neck 2 on the cup 1, is removably engaged by a correspondingly threaded collar 3 which depends from the bottom 4, of the upper section shaped to form a cylindrical air tight water chamber 5. As is apparent, the collar 3, and bottom 4, constitute a closure for the cup 1 making it air tight so that the gas generated may be effectively retained therein. The top of the chamber 5 is provided with a filling opening 6, and an upstanding exteriorly threaded collar 7 is formed about the opening while the opening is removably closed through the medium of a cap 8.

With a view to providing novel means for controlling and feeding water to the cup 1, from the chamber 5, I employ a tube 9 and rigidly connect it in a central opening in the top of chamber 5. The tube is also provided with a transverse opening 10, positioned so as to lie just above the upper surface of the bottom 4 and thereby allow water to enter the interior of the tube. The lower edge of the tube 9 terminates near the bottom of the cup 1 for a purpose that will presently appear. Arranged in telescopic relation with tube 9 is a tube 11 for controlling the flow of water through the tube 9. The lower end of the tube 11 is bifurcated to provide spaced portions 12 while the free ends of these portions are bent arcuately upon themselves to provide agitating arms 13 for the carbide within the cup 1. The bifurcation in the tube 11 is adapted for reg-

istration with the opening to allow the water which passes through the opening 10 to flow down the inside of the tube and fall upon the carbid in the cup so as to generate 5 gas therein. In order to rotate the tube and at the same time adjust the flow of water from the chamber 5 to the cup 1, I have threaded the upper end thereof as indicated by the numeral 14 and have arranged this 10 threaded end in the upper end of the tube 9 as indicated at 15. A finger piece 16 has a shoulder 17 formed thereon which is arranged in the slot 18 in the upper end of the tube 11 and retained therein by means of a 15 nut 19 which engages the upper threaded end of the tube and also the shoulder as indicated in the drawings.

For the purpose of providing suitable 20 means for allowing the gas to pass from the cup 1, I employ an elbow pipe 20, one portion of which is mounted in an opening in the bottom 4 while the other portion is mounted in a cylindrical opening in the bottom 21 of a screw threaded recess 22 in the 25 wall of the chamber 5.

As intimated, I have provided a reflector 23 which may be and preferably is of a concave form and to removably connect the reflector in the chamber I have formed on the 30 rear face thereof an exteriorly threaded collar 24, the threads of which correspond to threads in the recess 22 to facilitate engagement between these parts. Absorbent material 25 is arranged in the collar 24 and 35 serves to filter and purify the gas while the burner tip 27 is mounted centrally of the outer face of the reflector. An igniter 27 of any preferred form is mounted in the reflector 23 and in the present instance consists of an abrasive wheel 28 and a spark 40 producing element 29 which cooperates with the wheel 28 so that the gas which is being discharged from the burner tip may be readily ignited.

45 A handle 30 is connected to the outer surface of the cup 1 and serves as a suitable means whereby the lamp may be readily attached to a miner's cap.

The operation of the invention may be 50 reviewed as follows:

Assuming that the parts have been assembled in the manner described and that carbid has been placed in the cup 1 and water in the chamber 5 to allow water to 55 enter the cup 1 the finger piece 16 is engaged and rotated to adjust the threaded end 14 of the tube 11 in the tube 9 so as to consequently arrange the bifurcation and the opening 10 in registration which allows the 60 water to enter the opening and pass down the inside of the tube and fall upon the carbid whereupon gas is generated in the cup 1. The gas passes upwardly and out through the outlet pipe 20 and then to the burner

where it is ignited by actuating the igniter 65 27. By alternately rotating the finger piece 16 the arms 13 will agitate the carbid in the cup 1 so as to consequently effectively generate gas as the water falls from the tube. As is apparent the lower portion of the tube 70 9 supports the bifurcated portions 12 of the tube 11.

While I have shown what I deem to be the preferable form of my device, I do not wish to be limited thereto, as there might be 75 slight changes made in the details of construction and arrangement of parts without departing from the spirit of my invention.

Having thus described my invention what I claim as new and desire to secure by Letters Patent is:

1. An acetylene lamp including a sectional body embodying a carbid receiving and a gas generating cup and a superimposed water chamber, a water feeding tube disposed centrally through the bottom of the chamber and projecting into the cup and having the upper end connected to the top of the chamber and further provided with an opening near the bottom of the chamber 90 for establishing communication between the chamber and the cup, another tube telescopically received in the water feeding tube, the upper end of the last mentioned tube being adjustably mounted near its upper end in 95 the water feeding tube and projecting above the top of the chamber, the lower end of the last mentioned tube being bifurcated so as to coöperate with the opening in the water feeding tube in controlling the flow of water 100 to the cup, agitating arms formed on the free ends of portions of the tubes formed by the bifurcations, and an operating element connected to the upper projecting end of the last mentioned tube for partially rotating 105 and oscillating the last mentioned tube to allow water to flow through the opening and between the bifurcation into the cup and for actuating the agitating arms.

2. An acetylene lamp comprising a sectional body including a carbid receiving and gas generating cup and a superimposed water chamber, a water feeding tube disposed through the bottom of the chamber and positioned in the cup and having the upper ends rigidly connected to the top of the chamber, the said tube being also formed with an opening near the bottom of the chamber for establishing communication with the cup, another tube telescopically arranged within the first tube and having the upper portion threaded and arranged in adjustable threaded engagement with the top of the water feeding tube and projecting through both, the lower end of the last mentioned tube being bifurcated so that when the tube is partially rotated the space between the bifurcation will be alined with 115 120 125

the opening so as to permit the water flowing through the opening and into the cup, agitating arms formed on the lower bifurcated portions of the tube, the extreme upper end of the threaded portion of the tube being provided with a slot, a finger piece having a shoulder thereon receivable within the slot and designed to facilitate

partial rotation and oscillation of the tube and control the flow of water and also actuate the agitating arms, and a nut for removable engagement with the upper threaded portion of the tube and the shoulder for clamping the finger piece to the tube. 10

In testimony whereof I affix my signature. 15

JAMES H. POWERS.
